UNITED STATES PATENT OFFICE.

GEORGE M. PORTEOUS AND FREDERICK S. MILLER, OF CHICAGO, ILLINOIS.

DESIGN FOR A PHOTOGRAPH-EXHIBITOR STAND.

SPECIFICATION forming part of Design No. 18,873, dated January 15, 1889.

Application filed December 17, 1888. Serial No. 293,889. Term of patent 7 years.

To all whom it may concern:

Be it known that we, GEORGE M. PORTEOUS, a citizen of the United States, and FREDERICK S. MILLER, a subject of the Queen of Great Britain, both residing at Chicago, in the county of Cook and State of Illinois, have invented and produced a new and original Design for a Photograph-Exhibitor Stand, of which the following is a specification, reference being had to the accompanying drawing, forming part thereof.

Said drawing represents in elevation a photograph-exhibitor stand embodying our design, the leading feature of which consists in the stand having a set of downwardly-diverging legs having divided upper portions and single lower portions with segmental or part circular portions intermediate of their said upper and lower portions, substantially as shown in the drawing, and hereinafter more fully set forth.

In said drawing, A indicates the stand, hav-

ing a series of downwardly-diverging or flaring legs, α . These legs have divided upper portions, α' , and single lower portions, α^2 , which said upper and lower portions unite by segmental or part-circular portions α^3 . The effect of such arrangement is that the legs contract downwardly toward the segmental portions, which relieves any appearance of abrupt union between the parts α' and α^2 of the legs and gives a graceful appearance to the stand.

What we claim is—

The design for a photograph - exhibitor stand, consisting of the stand having flaring legs, with the upper divided leg portions, α' , the lower single leg portions, α^2 , and the segmental portions α^3 , substantially as shown and described.

GEORGE M. PORTEOUS.
FREDERICK S. MILLER.
